CLAIM

The ornamental design for a wristband for smartwatch, as shown and described.

DESCRIPTION

FIG. 1 is a front, left, top perspective view of a wristband for smartwatch, showing my new design;
 FIG. 2 is a front elevation view thereof;
 FIG. 3 is a rear elevation view thereof;
 FIG. 4 is a right elevation view thereof;
 FIG. 5 is a left elevation view thereof;
 FIG. 6 is a top plan view thereof; and,
 FIG. 7 is a bottom plan view thereof.
 The broken lines in the drawings represent portions of the wristband for smartwatch and form no part of the claimed design.
